SIDE BEARING

Roland J. Olander, Chicago, Ill., assignor to W. H. Miner, Inc., Chicago, Ill., a corporation of Delaware

Application March 7, 1941, Serial No. 382,131

13 Claims. (Cl. 308—226)

This invention relates to improvements in side bearings for railway cars.

One object of the invention is to provide a simple and efficient anti-friction side bearing for railway cars cooperating with the body and truck bolsters of the car and having rolling contact with one of said bolsters, wherein spring means is provided for maintaining the contact.

Another object of the invention is to provide an anti-friction side bearing including an anti-friction roller interposed between the bolsters of a railway car, which is supported by one of the bolsters and is yieldingly urged into engagement with the other bolster, thereby avoiding separation of the roller and the bolster with which it cooperates.

A further object of the invention is to provide a side bearing of the character set forth in the preceding paragraph, wherein the yielding contact of the roller is maintained by relatively heavy spring means adapted to cushion shocks transmitted from one of said bolsters to the other.

Other objects of the invention will more clearly appear from the description and claims herein-after following.

In the drawings forming a part of this specification, Figure 1 is a vertical sectional view taken parallel to the length of the car, through the ends of the body and truck bolsters, showing my improved side bearing in connection therewith, the side bearing being shown in elevation. Figure 2 is a top plan view of the side bearing shown in Figure 1. Figure 3 is a vertical sectional view, corresponding substantially to the line 3—3 of Figure 2. Figure 4 is a vertical sectional view, corresponding substantially to the line 4—4 of Figure 2.

In said drawings, 10 designates the bottom portion or flange of the body bolster and 11 the upper portion or flange of the truck bolster of a railway car. As shown, the underneath side of the body bolster 10 is provided with a hardened bearing plate of well-known form. The two bolsters are provided with the usual center bearing about which the bolsters have angular movement with respect to each other.

My improved side bearing comprises broadly a base member A; a housing B; a roller C; and a spring D.

The base member A comprises a heavy plate 12, provided with upstanding flanges 13 and 14, at opposite ends and laterally extending securing ears 15, 16, and 17. As shown, the ear 17 is located at one side of the plate and the remaining ears 15 and 16 at the other side thereof. The

ears 15 and 16 lie on opposite sides of a center line passing through the ear 17. Each of the ears is provided with an opening 18 adapted to receive a rivet 19, or similar fastening element by which the plate is secured to the truck bolster 11.

The flange 13 extends transversely of the plate and is curved or arc-shaped, as shown most clearly in Figure 2. The flange 14 extends transversely of the opposite end of the plate and has right angular inturned vertically disposed side portions 20—20 and a horizontally disposed inturned lip 21 at the upper edge thereof. The flange 14, together with the side portions 20—20 and the lip 21, forms an inwardly opening pocket or seat 121 for a purpose hereinafter described. The side portions 20—20 form the side walls of the pocket or seat and the lip 21 the top wall of the same. The back wall of the pocket or seat, which is formed by the transverse portion of the flange 14, is thickened at its base where it merges with the plate 12 and, as shown, the inner face or surface of said base portion of the flange is rounded concavely, as indicated at 22, to provide a bearing surface.

25 The housing B comprises longitudinally extending, vertical side walls 23—23, transversely extending vertical end walls 24 and 25, a transverse central partition wall 26, and a horizontal top wall 27. The top wall 27 extends from one side wall 23 to the other and from the end wall 24 to the partition wall 26. The partition wall 26 divides the housing into two compartments, one of which is open at the bottom and closed at the top by the wall 27, and serves as a spring pocket 28, and the other of which is open both at the top and bottom and serves as a container 29 for the roller bearing. The end wall 24 is of curved or arc-shaped transverse contour, the curvature thereof being concentric with the curvature of the flange 13 of the base plate 12. The partition wall is thickened at opposite sides and the surface thereof, which is opposed to the wall 24, is transversely curved or arc-shaped to provide, with the wall 24, a cylindrical opening or spring pocket. The opposite side of the partition wall 26 is substantially straight in transverse direction, as shown most clearly in Figure 2. The lower ends, or base portions of the opposed walls 25 and 26 are thickened, as shown, their inner faces or surfaces being concavely rounded, as indicated at 30—30.

At the right hand end, as viewed in Figures 1, 2, and 3, the housing B is provided with a relatively heavy, outwardly projecting, horizontal lip

or bearing lug 31 at its base portion, which is adapted to seat in the pocket 121. The lug 31 has its outer lower corner rounded off, as indicated at 32, to properly cooperate with the rounded inner bearing surface 22 at the base of the transverse section of the flange 14.

The portions of the walls 23-23 which form the side walls of the roller containing chamber are outwardly enlarged, as indicated at 132-132, to provide bearing supports for the trunnions of the roller C, as hereinafter will appear. The enlarged portions 132-132 of the walls are provided with bearing seats 33-33 which are open at the top. The seats 33-33 have concave bottom walls on which the trunnions of the roller C are adapted to rest. The outer walls of the seats 33-33, which are designated by 34-34, are relatively thin so that the upper end portions thereof may be bent or bowed inwardly, as indicated at 35-35, to overhang the trunnions of the roller and prevent accidental removal of the roller.

The roller C is in the form of a solid cylinder and has trunnions 36-36 which rest in the bearing seats 33-33 within which they are rotatable. As shown most clearly in Figures 1, 3, and 4, the roller C protrudes above the housing to properly contact the underneath surface of the body bolster 10.

The spring D is housed in the chamber 28 of the housing B and rests on the base plate 12. The upper end of the spring bears on the underneath face of the top wall 27 of the housing, thus normally holding the housing in the raised position shown in Figures 1 and 3. The top wall 27 of the housing is preferably provided with an inwardly protruding hollow boss 37 which extends into the coil of the spring D.

The housing B and the base member A are held assembled by a retainer bolt 38 having its head 39 anchored to the base plate 12 of the base member A. The shank of the bolt 38 extends through aligned openings in the base plate 12 and the bottom wall of the hollow boss 37, and the bolt is anchored at its upper end to said boss by the nut 40 thereof, which is accommodated in the opening of the boss.

As shown most clearly in Figure 3, the bottom side of the housing B is convexly rounded transversely to permit transverse rocking adjustment of the housing on the base plate 12. As further shown in Figure 3, the lug 31 of the housing B fits the seat 121 rather loosely to permit this rocking movement. The bottom side of the housing is inclined upwardly with respect to the top side thereof from the end which is provided with the lug to the other end thereof, thus leaving a certain amount of clearance between the base plate 12 and the lower side of the housing at the spring chamber end of the latter to allow upward and downward rocking of the housing on its lug 31 as a pivot. The expansive action of the spring D constantly holds the roller C against the bearing surface of the body bolster. As will be evident the effective capacity of the spring is greatly multiplied due to the lever action of the housing B, the spring being at the outer end of the long arm of the lever which extends from the pivot lug 31 to the spring chamber, and the roller C being at the end of the short arm which extends from the pivot lug 31 to the point of support of the roller C.

I have herein shown and described what I now consider the preferred manner of carrying out my invention, but the same is merely illustrative and I contemplate all changes and modifica-

tions that come within the scope of the claims appended hereto.

I claim:

1. In a side bearing for a railway car having body and truck bolsters, the combination with a supporting member pivoted at one end on one of said bolsters, said pivoted end being held against movement toward said last named bolster; of a roller rotatably supported on said member between the ends of the latter; and spring means engaging said member at the end thereof remote from its pivot and forcing said member toward the other bolster.

2. In a side bearing for a railway car having body and truck bolsters, the combination with a lever; of a supporting bearing element on one of said bolsters, supporting one end of said lever against movement toward said bolster and mounting said lever for swinging movement about said end; of a spring forcing the lever to rock about said end toward the other bolster; and a roller rotatably mounted on said lever at a point between the pivot thereof and the point of application of spring pressure.

3. In a side bearing for a railway car having body and truck bolsters, the combination with a base member secured to one of said bolsters; of an anti-friction roller; a support on which said roller is rotatably mounted, said support being pivoted at one end on said base member, said pivoted end being held against movement toward said bolster; and a spring reacting between said support and the base member to rock the support on its pivoted end, the application of the spring pressure to said support being more remote from the pivot thereof than the roller.

4. In a side bearing for a railway car having body and truck bolsters, the combination with a base member secured to one of said bolsters; of a housing having rocking engagement at one end on said base member; a spring interposed between said housing and base member at the other end of the housing to yieldingly support said last named end of the housing; and an anti-friction roller rotatably supported in said housing between the ends thereof and projecting therefrom to engage the other bolster, the ends of said housing being pressed respectively against said base member and spring by engagement of the roller with said last named bolster.

5. In a side bearing for a railway car having body and truck bolsters, the combination with a base member secured to one of said bolsters; of a housing pivoted at one end on said base member, said pivoted end being held against movement toward said last named bolster; an anti-friction roller supported in said base member between the ends thereof and projecting therefrom; and a spring at the other end of said housing interposed between the latter and the base member to swing the housing on its pivot in a direction away from said base member.

6. In a side bearing for railway cars, the combination with a base member; of a housing pivoted at one end only on said base member for swinging movement toward and away from said base member, said pivoted end being confined against movement toward said base member; a spring interposed between said housing and base member to swing the housing on its pivot; and an anti-friction roller mounted in said housing intermediate the pivot thereof and the point of application of the spring pressure, said roller projecting from the housing, the axis of rotation

of said roller being fixed with respect to the housing.

7. In a side bearing for railway cars, the combination with a base member; of a housing pivoted at one end on said base member for rocking movement longitudinally, said housing and base member having opposed bearing surfaces, one of which is crowned transversely to permit lateral rocking of the housing on said base member; an anti-friction roller mounted in the housing and projecting therefrom; and spring means interposed between the base member and housing at a point spaced from said pivoted end of the housing to swing the latter on its pivoted end away from the base member.

8. In a side bearing for railway cars, the combination with a base member having a flat top bearing surface; of a housing pivoted at one end on said base, said housing having a transversely rounded convex bottom face having transverse rocking engagement with the flat top surface of the base member; a spring interposed between the base member and the housing at a point remote from the pivot of the latter, said spring yieldingly supporting the housing on said base member; and an anti-friction roller rotatably supported in the housing at a point less remote from the pivot thereof than the spring.

9. In a side bearing, the combination with a base member; of a housing pivoted at one end on said base member, said pivoted end bearing on top of said base member in rocking engagement therewith, said housing having a spring pocket remote from the pivot thereof; an anti-friction roller mounted in the housing between the pivot and the spring pocket thereof, said spring pocket being closed at the top; and a spring seated in said pocket, said spring being interposed between the base member and the closed end of the pocket.

10. In a side bearing, the combination with a base member having a pivot seat at one end including vertically spaced top and bottom abutment walls; of a housing having a lug at one end engaged in said seat between said top and bottom walls thereof for pivotal movement on said bottom wall; a spring reacting between said base and the other end of the housing to swing the

latter on its pivot; and an anti-friction roller, rotatably mounted in the housing between the ends of the same.

11. In a side bearing, the combination with a base member; of a housing having a spring chamber at one end and a roller containing chamber at the other end, said spring chamber being closed at the top and said roller chamber being open at the top, said housing being pivotally supported at one end on said base member, said pivoted end being held against movement toward said base member; an anti-friction roller rotatably mounted in said roller chamber and protruding through the open top thereof; and a spring in said spring chamber and bearing on the base member and closed end of said spring chamber respectively.

12. In a side bearing, the combination with a base member; of a housing pivoted at one end on said base member, said housing having a spring chamber and a roller chamber, said spring chamber being more remote from the pivoted end of the housing than the roller chamber; spring means within the spring chamber bearing on said base member to force the spring chamber end of the housing away from the base member; a retainer bolt anchored to the base member and housing for limiting the swinging movement of the housing away from said base member; and an anti-friction roller rotatably mounted in said roller chamber.

13. In a side bearing, the combination with a base member having an upstanding transverse flange at one end provided with an inturned ledge at its upper end; and a fulcrum bearing face beneath said ledge and spaced therefrom; a housing supported on said base member, said housing having a pivot lug at one end engaged under said ledge in bearing engagement with said fulcrum bearing face; spring means interposed between the housing and base member at the end of the housing remote from the pivoted end thereof to yieldingly force the housing away from the base member; and an anti-friction roller mounted in the housing between the ends of the latter.

ROLAND J. OLANDER.
